FILE RACK FOR A DESK TOP

Thomas G. Pond, Fresno, Calif., assignor to Lit-Ning Products Company, a corporation of California

Filed Sept. 22, 1966, Ser. No. 3,973

Term of patent 14 years

(Cl. D33—2)

FIG. - 1

FIG. - 2

FIG. - 3

FIG. - 4

FIG. 1 is a perspective view of a file rack for a desk top in accordance with my new design, showing the left side, front and top thereof;

FIG. 2 is a front elevation of a file rack for a desk top in accordance with my new design;

FIG. 3 is an elevation of the right side of the file rack for a desk top of FIG. 1; and

FIG. 4 is a rear elevation of the file rack for a desk top of FIG. 2.

The file rack for a desk top of my invention may have variable lateral dimensions and the file rack for a desk top is shown broken away to indicate indeterminate length in FIGS. 1, 2 and 4.

I claim:

The ornamental design for file rack for a desk top, as shown and described.
